J. B. HOWLE

PUNCH

Filed June 30, 1922

UNITED STATES PATENT OFFICE.

JAMES B. HOWLE, OF RICHMOND, VIRGINIA.

PUNCH.

Application filed June 30, 1922. Serial No. 571,908.

To all whom it may concern:

Be it known that I, JAMES B. HOWLE, a citizen of the United States, residing at Richmond, in the county of Henrico and State of Virginia, have invented certain new and useful Improvements in Punches, of which the following is a specification.

This invention relates to tools, and the primary object of the invention is to provide a novel punch so constructed as to form a slot and tongue in the meeting terminals of a pair of pipe sections to permit the ready connection of sheet metal pipes together without the usual trouble of riveting or bolting the same.

Another object of the invention is to provide an improved tool which will both form the tongue and slot in the meeting terminals of the sheet metal pipe sections, thereby eliminating the necessity of providing independent tools for striking out the tongue in one section and for forming the slot in the other section.

A further object of the invention is to provide a novel punch for the above stated purpose, which embodies a pair of pivotally associated members, each of said members having oppositely disposed jaws formed on the opposite sides of the pivot point of said members, the pairs of jaws carried by said members being so formed as to form an outstruck tongue and a slot in the pipe sections.

A further object of the invention is to provide novel dies carried by said jaws whereby the outstruck tongues and slots will be readily formed in the work.

A further object of the invention is to provide a novel means for adjusting the dies carried by the jaws, so that the wear on said dies can be taken up when necessary.

A still further object of the invention is to provide a novel double punch of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a longitudinal section through the improved punch showing the same in use for forming a slot in a pipe section, the pipe section being shown in longitudinal section.

Figure 2 is a fragmentary longitudinal section through the improved tool, showing the same in use for forming an outstruck tongue, in the companion pipe section, the pipe section being shown in longitudinal section.

Figure 3 is a detail section through the head of the tool taken on the line 3-3 of Figure 2.

Figure 4 is a detail section through the head of the tool taken at right angles to Figure 3 on the line 4-4 of Figure 2, looking in the direction of the arrows.

Figure 5 is a similar view taken on the line 5-5 of Figure 2, looking in the direction of the arrows.

Figure 6 is a longitudinal section through one of the handles of the companion members, showing the spring carried thereby for normally holding the jaws of the members in spread condition in relation to each other.

Figure 7 is a fragmentary detail perspective view of a pair of sheet metal pipe sections connected together by the improved tongue and slot connection formed by the improved tool.

Figure 8 is a detail edge elevation of the head of the tool showing the die carried by one side of the tool for forming the slot in one of the pipe sections.

Referring to the drawings in detail, wherein similar reference characters designate corresponding parts throughout the several views, the letters A and B indicate the companion members of the improved punch.

The member A is preferably formed from two flat plates 10 and 11, each of which are T-form and include the flat heads 12 and the rearwardly extending shank portions 13 which are bowed arcuately throughout their lengths. The shank portions 13 of the companion plates 10 and 11 are also bowed transversely toward each other to form a suitable handle or hand grip 14. These companion plates 10 and 11 of the handle A can be held together in any preferred manner, such as by rivets 15 or screws. The heads 12 of the plates 10 and 11 are disposed in spaced relation to each other

so as to permit the head 16 of the member B to be arranged therebetween as will be hereinafter more fully apparent as the description proceeds. These heads 12 are also held in spaced relation by cross strips or bars 17 and 18. Each of the plates 10 and 11 have the head portions 12 thereof provided with inwardly extending aligned slots 19 and 20 which terminate short of the longitudinal center of the said heads. The opposite walls of the pairs of slots 19 and 20 support respectively the anvil portions 21 and 22 of the slot forming device C and the tongue forming device D. These anvil portions 21 and 22 will be hereinafter more fully described.

The companion member B includes the head 16 and arcuate bowed shank portion 23, which forms the companion hand grip for the hand grip portion 14 of the member A. As clearly shown in Figure 1 of the drawings, the head 16 has extending outwardly from the opposite sides thereof the arms 24 and 25 which carry respectively the cutting portions 26 and 27 of the slot and tongue punching implements C and D. The arms 24 and 25 are disposed on opposite sides of the axis of the head 16 so that the cutting portions 26 and 27 of the slot cutting device C and the tongue striking out punch D will engage the respective anvils 21 and 22 simultaneously.

In order to normally hold the cutting portions 26 and 27 away from their anvil portions 21 and 22 of the slot cutting and tongue punching devices C and D, a leaf spring 30 is provided. This leaf spring 30 has formed on its inner end the attaching plate 31 which can be inserted in suitable grooves 32 formed in the inner faces of the handle or shank portions 13 of the plates 10 and 11. This spring 30 is bowed outwardly and engages the shank or handle portion 23 of the member B, and thus normally tends to rock the member B on the pivot pin 33, which connects the member B with the member A. While I have shown a leaf spring for normally holding the cutting portion away from the anvil, it is to be understood that an equivalent can be used in lieu thereof.

The slot cutting device C, as stated, includes the anvil portion 21 and the cutting portion 26. The anvil portion 21 consists of a flat body plate formed of suitable material, such as tool steel, and is provided with a longitudinally extending rib 35, which fits intermediate the heads 12 of the plates 10 and 11. The edges of the body plate of the anvil 21 rest upon the walls of the slots 19, formed in the head 12 of the plates 10 and 11. The anvil can be held against movement by means of a suitable screw 36, which extends through the strip 17, and this screw 36 can also be utilized for

adjusting the anvil within certain limits. Adjacent to the forward transverse edge of the anvil 21, an indentation or transverse groove 37 is provided for the cutting portion 26.

The cutting portion 26 consists of a face plate 38 which is fitted on the outer end of the arm 24 and held in place by means of a suitable screw or the like 39. The inner edge of the face plate 38 is enlarged and provided with a straight cutting edge 40. As clearly shown in Figure 1 of the drawings, the outer face of the arm 24 can be bevelled to receive the enlarged end of the said base plate 38.

The extreme forward end of the anvil 21 is curved arcuately as at 21' in order to permit the same to conform to the curvature of a pipe which is to be cut, and the same will form a complete rest for the entire surface of the pipe being cut.

The tongue cutting device D includes, as heretofore stated, the anvil portion 22 and the cutting portion 27, and these portions are carried respectively by the heads 12 of the plates 10 and 11 of the member A and by the arm 25 of the head 16 of the member B. The anvil 22 is formed similar to the anvil 21 and includes a flat plate having an enlarged longitudinally extending rib 41 which fits intermediate the heads 12. The opposite longitudinal edges of the flat plate or body portion of the anvil fit upon the walls of the slots 20 which are opposite the walls of the slots 19 on which the anvil 21 is placed. This anvil 22 can be held in place by means of the screw 22 which is extended through the strip or bar 18 and it can be seen that by turning the screw 42, the anvil 22 can be adjusted within certain limits. The active face of the anvil 22 is provided with a recess 43, the inner wall of which is bevelled or inclined as at 44 to form a guide for the tongue being struck and cut out.

The cutting portion 27 of the tongue cutting and striking out device C includes a pair of right angularly extending base plates 45 and 46 which are fitted in suitable rabbeted portions of the outer end and inner face of the arm 25. As shown, the cutting portion 27 is removably held in place by means of a suitable screw or the like 47. The plate 27 is provided with a raised inclined substantially semi-circular shaped cutting surface 48 which forms means for stamping and cutting out the tongues. It is preferred that the substantially semi-circular cutting portion 48 have its inner face depressed as at 49. As clearly shown in Figure 1 of the drawings, this semi-circular cutting knife 48 inclines inwardly toward the head portion 16.

In Figure 1 of the drawings is shown the improved tool in use on a pipe section E

and the tool is placed in position so that one end of the pipe section will rest in the slots 19. This will position the anvil 21 on the inside of the pipe, with the curved edge 21' in engagement therewith. When pressure is applied to the hand grips 14 and 23, the sharpened end 40 of the cutting portion 26 will be brought into forcible engagement with the pipe section and thus cut a straight slot 50 therein. Owing to the inclined surface of the depression 37, the force of the metal will be pushed inwardly as indicated by the reference character 51. On one side of the pipe section E is shown the slot already formed.

In Figure 2 of the drawings is shown the tool operating on a pipe section F forming the struck out tongues 52 therein.

In forming the struck out tongues 52 in the pipe section F, the pipe section is placed in the slot 20 with the anvil portion 22 in engagement with the outer surface of the pipe, after which pressure is applied to the hand grips 14 and 23 which will bring the cutting edge 48 into engagement with the pipe and strike out the tongue 52 therefrom. Owing to the inclination of the cutting edge 48 and the inclined anvil 22, the tongue will be struck outwardly at an incline as clearly shown in Figures 2 and 7 of the drawings.

It is contemplated making the slots 50 and the tongues 52 at diametrically opposite points on the pipe sections, but of course, it is to be understood that as many slots and tongues may be formed in the pipe sections as may be desired.

In Figure 7 of the drawings is shown the pipe sections E and F in their assembled position, showing the manner in which the tongues 52 protrude through the slots 50.

From the foregoing description, it can be seen that an improved tool has been provided which will effectively cut both slots and tongues in opposite sections of sheet metal pipes for facilitating the connection thereof.

Changes in details may be made without departing from the spirit or scope of this invention; but

I claim:

1. A single tool for forming slots and tongues in sheet metal pipes comprising a pair of companion members, each of said members including a head, means pivotally connecting the heads together, oppositely disposed outwardly extending jaws formed on each side of each head, and cooperating dies including adjustable anvils, and cutting and punching devices carried by the opposite faces of said jaws.

2. A single tool for forming slots and struck out tongues in sheet metal pipes comprising a pair of members each including a head, and an operating handle, means for pivotally connecting the heads together, op-

ositely extending jaws formed on each of the heads on opposite sides of the pivot point thereof, anvils carried by the opposite faces of the jaws formed on one of said members and cutting and punching dies 70 formed on the opposite faces of the jaws carried by the other member for cooperating with said anvils.

3. A single tool for cutting slots and punching tongues in work comprising a 75 pair of companion members, one of said members including a head having a pair of spaced plates and a rearwardly extending handle, the other member including a head disposed intermediate said 80 plates and a rearwardly extending handle, a pivot pin connecting the heads together, the head of the first mentioned member having inwardly extending slots formed therein, the head of the other member having outwardly extending arms formed thereon, anvils carried by the opposite walls of the slots, and slot cutting and tongue punching members carried by the opposite faces of the arms for cooperation with said 90 anvils.

4. A single tool for cutting slots and forming struck out tongues in work comprising a pair of companion members, one of said members including a head having a 95 pair of spaced plates and a rearwardly extending handle, the other members including a solid head disposed between said plates and a rearwardly extending handle, a pivot pin connecting said heads together, 100 the plates forming said head of the first mentioned member having inwardly extending slots formed in the opposite edges thereof, outwardly extending arms formed on the head of the other member, means of holding the plates of the first mentioned head in spaced relation including strips disposed adjacent to said pairs of slots, an anvil plate carried by the opposite walls of said slots, screws extending through said strips 110 and engaging said plates for holding said plates in engagement with the walls of the slots, and slot cutting and tongue punching dies carried by the opposite faces of said arms for engaging said anvils. 115

5. A single tool for cutting slots for punching out tongues in sheet metal work comprising a pair of companion members each including heads, means pivotally connecting the heads together, an anvil plate 120 carried by one of said heads having a transverse groove formed therein, the groove being provided with an inclined rest wall, a slot cutting die carried by the other head having an inclined face arranged to engage 125 the said rest wall, the forward edge of said anvil plate being curved arcuately, as and for the purpose specified.

6. In a tool for cutting slots and striking out tongues in sheet metal work comprising 130

a pair of companion members each includ-
ing a head, means pivotally connecting the
heads together, an anvil plate carried by
one head including a face plate having an
inclined rest wall, a tongue punching die
carried by the other head including a pair
of angular related face plates and a semi-
circular cutting head, said semi-circular cut-
ting head being disposed at an incline and
arranged to engage said inclined rest wall, 10
and spring means holding the handle and
punch cutting die in spaced relation.

JAMES B. HOWLE.
